DESIGN FOR A WELDING ELECTRODE HOLDER

Eric Siemers, Kalamazoo, Mich., assignor to
Roscoe B. Lacey, Kalamazoo, Mich.

Application January 6, 1945, Serial No. 117,307

Term of patent 7 years

(Cl. D26—1)

To all whom it may concern:

Be it known that I, Eric Siemers, a citizen of the United States, residing at Kalamazoo, in the county of Kalamazoo and State of Michigan, have invented a new, original, and ornamental Design for Welding Electrode Holder, of which the following is a specification, reference being had to the accompanying drawing forming part thereof:

In the drawing:

Figure 1 is a top plan view of a welding electrode holder embodying my new design;

Figure 2 is a side elevational view of the welding electrode holder; and

Figure 3 is a front end view of said holder.

I claim:

The ornamental design for a welding electrode holder, as shown.

ERIC SIEMERS.
